(57) **CLAIM**

The ornamental design for a hallux valgus corrector, as shown and described.

DESCRIPTION

FIG. 1 is a front and bottom perspective view of a hallux valgus corrector, showing my new design;

FIG. 2 is a rear and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged perspective view of detail "9" identified in FIG. 1.

The dashed lines in the figures illustrate portions of the hallux valgus corrector that form no part of the claimed design. The dash dot dash lines in FIGS. 1 and 9 depict the boundaries of the enlarged views and form no part of the claimed design.

1 Claim, 9 Drawing Sheets
